(57) **CLAIM**

The ornamental design for a slanted pitcher, as shown and described.

DESCRIPTION

FIG. 1 is a perspective view of the slanted pitcher according to the invention;

FIG. 2 is a side view of the slanted pitcher;

FIG. 3 is a top view of the slanted pitcher;

FIG. 4 is a bottom view of the slanted pitcher;

FIG. 5 is a front view of the slanted pitcher; and,

FIG. 6 is a rear view of the slanted pitcher.

The broken line showing of structure is for illustrative purposes only and forms no part of the claimed design.

The broken lines in the drawings are for illustrative purposes only and form no part of the claimed design.

1 Claim, 4 Drawing Sheets
